[57]

ABSTRACT

The invention concerns new carboxylic acid amides of the formula

wherein M denotes a divalent bridge member of the series —S—, —S—A—S— and —S—CH₂—CH₂—(O—CH₂—CH₂)_p—S—, A denotes an alkylene residue containing one to 18 carbon atoms, p denotes an integer from one to three, R₁ denotes an alkyl group and R₂ denotes alkyl or hydrogen.

These compounds are valuable antioxidants for polymers which are damaged by oxidative attacks.

4 Claims, No Drawings

CARBOXYLIC ACID AMIDES

The subject of the invention is the new carboxylic acid amides of formula

(1)

wherein M denotes a divalent bridge member of the series —S—, —S—A—S— and —S—CH₂—CH₂—(O—CH₂—CH₂)_p—S—, A denotes an alkylene residue containing 1 to 18 carbon atoms, p denotes an integer from one to three, R₁ denotes an alkyl group with one to eight carbon atoms and R₂ denotes hydrogen or an alkyl group with one to eight carbon atoms. Here the total number of carbon atoms for all "A" members normally does not amount to more than 36, preferably not more than 26.

In this formula, the alkylene residues A can be both straight-chain and branched in nature, but in any case represent divalent saturated residues. The substituents R₁ and R₂ can also be straight-chain or —preferably—branched in nature. Though both of the positions which are in each case possible for R₁ and R₂ can be considered, these residues are preferably in the o-position to the hydroxyl group.

Compounds of formula (1) of predominant practical interest are those which correspond to the formula

(2)

wherein M₁' denotes a divalent bridge member —S—, —S—(CH₂)_q—S— or —S—CH₂—CH₂—O—CH₂—CH₂—S—, q denotes an integer from one to six, n denotes an integer from one to 12, R₁ denotes an alkyl group with one to eight carbon atoms, R₂ denotes hydrogen or an alkyl group with one to eight carbon atoms and R₂' denotes hydrogen or an alkyl group containing one to four carbon atoms. In view of the fact that formula (2) lies within the framework of formula (1), it is obvious that R₂ and R₂' cannot simultaneously be different from hydrogen.

Especially preferred types of compounds are those of the compounds of formula

(3)

wherein M₁ denotes a divalent bridge member —S— or —S—(CH₂)_q—S—, q denotes an integer from 1 to 6, n denotes an integer from 1 to 12, R₁ denotes an alkyl group with one to eight carbon atoms and R₂ denotes hydrogen or an alkyl group with one to eight carbon atoms (with the alkyl group for R₁ and R₂ in particular containing one to four carbon atoms), and furthermore compounds of formula

(4)

wherein M₁ denotes a divalent bridge member —S— or —S—(CH₂)_q—S—, q denotes an integer from one to six, m denotes an integer from one to four, and R₃ denotes a branched alkyl group containing one to four carbon atoms.

The compounds defined above can be manufactured analogously to procedures which are in themselves known. The compounds according to formula (1) — and analogously, those of the subordinate formulas — can appropriately be obtained by reacting about two mols of a compound of formula

75

(5)

with about one mol of a mercaptan of formula

(6)

15

in the form of its alkali salt, with R₁, R₂, A and M having the abovementioned significance and Hal representing a halogen atom.

Compounds of formula (2) are for example obtained entirely analogously by reacting about two mols of a compound of formula

(7)

with about 1 mol of a mercaptan of formula

(8)

in the form of its alkali salt, with R₁, R₂, R₂', n and M₁' having the abovementioned significance and Hal representing a halogen atom.

In the case where M₁ = —S—, compounds of formula (5) are for example condensed with sodium sulphide.

In the case where M₁ = —S—(CH₂)_q—S—, wherein q has the indicated significance, compounds of formula (5) are appropriately reacted with the alkali salts of dithiols formula

9

in a solvent which is inert towards the reagents (for example alcohols or hydrocarbons).

The alkali salts of the dithiols can be manufactured in the presence of a solvent by using the alkali metal, or through the use of the stoichiometric amount of an alkali alcoholate. The compounds of formula (5) required as starting substances are obtained by the reaction, which is in itself known, of acid ha-

60

lides, preferably acid chlorides, of formula

10

with p-aminophenols of formula

(11)

wherein A, Hal, R₁ and R₂ have the abovementioned significance. This reaction is carried out in the presence of a solvent which is inert towards the reagents, with the corresponding hydrogen halide acid being split off. The resulting hydrogen halide acid can be removed from the reaction mixture by sucking-off, or be bonded by adding a hydrogen halide acceptor, (for example a tertiary amine).

The compounds of formula (1) and of the subordinate formulas are suitable for stabilizing oxidation-sensitive organic materials against oxidation. For this purpose they can be used in a manner which is in itself known for the following substrates: homopolymers and copolymers of ethylenically unsaturated compounds such as vinyl chloride, vinylidene chloride, styrene, butadiene, isoprene, ethylene, propylene, acrylic and methacrylic acid derivatives, for example acrylic acid alkyl esters, acrylamides and acrylonitrile; polyamides, for example from ϵ -caprolactam or from adipic acid and a diamine; polyesters such as polyterephthalic acid glycol ester; natural and synthetic rubbers; lubricating oils; petrol; vegetable and animal oils and fats; waxes; cellulose and cellulose derivatives such as cellulose esters.

The compounds defined above are of preferred importance as stabilizers against oxidative influences in the case of polymerization products of α -olefines, that is to say in the case of homopolymers and copolymers of α -olefines such as preferably ethylene or propylene, and also in the case of substrates which predominantly contain homopolymers or copolymers of α -olefines.

For a good antioxidant effect, small amounts of compounds of formula (1), that is to say about 0.01 to two percent relative to the amount of the substrate to be protected, in general suffice. The antioxidants can for example be incorporated into the materials to be protected directly, that is to say by themselves, or together with other additives such as plasticizers, pigments, light protection agents or optical brighteners, and/or with the aid of solvents.

The antioxidative effect of the compounds of formula (1) also manifests itself in the light exposure test, in that these compounds are able to prevent or greatly to reduce oxidative processes induced by the action of light, for example the yellowing of polyethylene.

The symbols used in the formulas of the present description, such as R_1 , R_2 , m and n , throughout have the same significance which has been precisely circumscribed at least once. In the manufacturing instructions and examples which follow the parts denote parts by weight and the percentages denote percentages by weight unless otherwise stated.

EXAMPLE 1

1.6 g of crystalline 61 percent strength sodium sulphide are dissolved in 100 ml of methanol. 7.425 g of the compound of formula

dissolved in 10 ml of methanol are added thereto. The reaction solution is heated for 30 minutes to reflux temperature and is thereafter mixed with activated charcoal, filtered and concentrated to dryness.

5 Yield of crude product: 6.0 g (86.5 percent).

The product for analysis, recrystallized from methylene chloride/cyclohexane, of the compound of formula

15 shows the following data:

Melting point: 228° to 229° C.

Analysis: calculated: C 69.03 H 8.69 N 5.03

found: C 68.87 H 8.65 N 5.00

The compound of formula

used as the starting material is manufactured as follows: 23.5 g of 2,6-di-tert. butyl-p-nitrosophenol are dissolved in 80 g of 5 N sodium hydroxide and diluted with 160 ml of water. A solution of 70 g of sodium hydrosulphite in 300 ml of water at about 50° C is added dropwise thereto while stirring. After completion of the addition of the sodium hydrosulphite the mixture is stirred for a further hour. The resulting crystal suspension is filtered off and washed with water until neutral. The moist filter cake of 2,6-di-tert.-butyl-p-aminophenol thus obtained is dissolved in 500 g of methylene chloride and separated from the aqueous phase. The methylene chloride phase is dried over sodium sulphate. After removing the drying agent, the mixture is concentrated to 300 g, 45 g of chloracetyl chloride are added dropwise at 20 to 30° C, and the whole stirred for 3 to 5 hours at reflux temperature until no further significant elimination of hydrogen chloride is detectable. The mixture is then finally stirred overnight at room temperature. Thereafter a few solid constituents are filtered off and the reaction solution is concentrated to dryness in vacuo. Yield of crude product: practically quantitative.

The products for analysis, recrystallized from cyclohexane, of formula (12) show the following data:

50 Melting point: 153° to 154°C

Analysis: calculated: C 64.53 H 8.12 N 4.70

found: C 64.38 H 8.17 N 4.77

The compounds quoted below are obtained in an analogous manner

The compounds of formula

(5a)

are obtained from the dried methylene chloride extracts.

The product for analysis, recrystallized from acetone/water, shows the following data:

Melting point: 200° to 201°C.

5 Analysis: calculated: C 66.19 H 8.50 N 4.54

found: C 65.91 H 8.53 N 4.46

The compounds quoted below are obtained in an analogous manner:

EXAMPLE 2

The mercaptide of 1,2-ethanediol is manufactured by introducing 580 mg of sodium into a solution of 1,2-ethanediol in 20 ml of absolute alcohol. 7.45 g of the compound of formula

dissolved in 70 ml of absolute ethanol are added to this solution. Thereafter the reaction solution is heated to reflux temperature for one hour and subsequently concentrated to dryness in vacuo, and the residue is taken up in methylene chloride and extracted by shaking with water. 4.0 g of crude product of the compound of formula

55 A mixture of 100 g of unstabilized polypropylene (Profax 6501, Hercules powder) and 0.2 g of a compound according to the table given below is worked into a hide on a calender at 170°C and subsequently pressed into a one mm thick sheet at 230°C and a pressure of 40 kg/cm². The sheets thus obtained are subjected to an accelerated oxygen ageing at 140°C (air, normal pressure). The time which elapses until the first visually perceptible cracks arise is a measure of the antioxidant effect of the added compound.

EXAMPLE 4

In parallel experiments, freshly distilled olive oil is oxidized for 20 minutes at 140° C in a pure oxygen stream, both without additives and also with the addition of, in each case, 0.2 percent by weight of the compounds quoted in Table 5 below. Thereafter one g of the batch is dissolved in a mixture of 20 ml of carbon tetrachloride, 20 ml of chloroform and 20 ml of freshly distilled glacial acetic acid. The oxygen dissolved in the form of a gas is expelled by means of a strong stream of nitrogen, after which one ml of saturated potassium iodide solution is added. The mixture is then well stirred for five

minutes under a nitrogen atmosphere so as to result in a quantitative separation of iodine. After adding 100 ml of freshly distilled water and a little starch solution as the indicator, the mixture is immediately back-titrated with 0.002 N sodium thiosulphate solution until the blue color disappears.

Peroxide number (= milliequivalents of peroxidic oxygen)/kg = ml (sodium thiosulphate solution) · 2

EXAMPLES

A mixture of 100 g of polyethylene powder (Microthene)

722, USI) and 0.2 g of one of the compounds mentioned in Table 6 is aged at 85°C for 16 hours in a circulating air oven. Thereafter the melt index is determined according to ASTM Specification D-1238-62-T. The melt index equals the amount of polyethylene, in grams, which has flowed in 10 minutes through a standard die, and represents a measure of

the degradation of the polymeric material. In a comparison experiment, the melt index of polyethylene samples without additives is determined.

TABLE 6

		Melt index
10	Polyethylene, without additive, not aged	3.48
	Polyethylene, without additive, aged	3.81
	Polyethylene with 0.2 part of the compound 13 (Example 1)	3.56
15	Polyethylene with 0.2 of the compound 26 (Example 2)	3.50
	Polyethylene with 0.2 part of 2,6-di-tert.butyl- 4- methylphenol	3.53
	Polyethylene with 0.2 part of methylene-bis- (3-methyl-4-hydroxy-5-tert.butylbenzene)	3.63

We claim:

1. A carboxylic acid amide of the formula

30 wherein M denotes a divalent bridge member of the series, —S—A—S— and —S—CH₂—CH₂—(O—CH₂—CH₂)_p—S—, A denotes an alkylene containing one to 18 carbon atoms, p denotes an integer from one to three, R₁ denotes an alkyl group with one to eight carbon atoms and R₂ denotes hydrogen or an alkyl group with one to eight carbon atoms.

2. A carboxylic acid amide according to claim 1, which corresponds to the formula

wherein M_1' denotes a divalent bridge member $—S—(CH_2)_q—S—$ or $—S—CH_2—CH_2—O—CH_2—CH_2—S—$, q denotes an integer from one to six, n denotes an integer from one to 12, R_1 denotes an alkyl group with one to eight carbon atoms, R_2 denotes hydrogen or an alkyl group with 1 to eight carbon atoms and R_2' denotes hydrogen or an alkyl group containing one to four carbon atoms; R_2 and R_2' cannot simultaneously be different from hydrogen.

3. A carboxylic acid amide according to claim 1 which corresponds to the formula

50 wherein M_1 denotes a divalent bridge member $—S—(CH_2)_q—S—$, q denotes an integer from one to six, n denotes an integer from one to 12, R_1 denotes an alkyl group with one to eight carbon atoms and R_2 denotes hydrogen or an alkyl group with one to eight carbon atoms.

55 4. A carboxylic acid amide according to claim 1, which corresponds to the formula

wherein M_1 denotes a divalent bridge member $—S—(CH_2)_q—S—$, q denotes an integer from one to six, m denotes an integer from one to four and R_3 denotes a branched alkyl group containing up to four carbon atoms.
